(57) **CLAIM**

The ornamental design for a valve and temperature control, as shown and described.

DESCRIPTION

FIG. 1 is a left side elevational view of a valve and temperature control according to the present invention, the right side elevational view being a mirror image thereof.

FIG. 2 is a front elevational view of the valve and temperature control of FIG. 1, the rear of the valve and temperature control being unornamented.

FIG. 3 is a top plan view of the valve and temperature control of FIG. 1.

FIG. 4 is a bottom plan view of the valve and temperature control of FIG. 1; and,

FIG. 5 is a perspective view of the valve and temperature control of FIG. 1.
